United States Patent Office.

J. H. BUTTS, OF STROUDSBURG, PENNSYLVANIA.

Letters Patent No. 81,876, dated September 8, 1868.

MEDICAL COMPOUND.

The Schedule referred to in these Letters Patent and making part of the same.

TO ALL WHOM IT MAY CONCERN:

Be it known that I, J. H. BUTTS, of Stroudsburg, in the county of Monroe, and in the State of Pennsylvania, have invented certain new and useful Improvement in Compound for Curing Rheumatism; and do hereby declare that the following is a full, clear, and exact description thereof.

The nature of my invention consists in a compound for the cure of rheumatism, gout, and all kindred diseases, and is made of the following ingredients:

For rheumatism, one pound smartweed and one-quarter of a pound of hops, which are to be put in one and a half gallon boiling water; then let them boil about five minutes, and cool off by the application of cold water to the outside of the vessel in which the compound is boiled.

For gout, add one-quarter of a pound of alum and one pound of white-oak bark, and boil and cool as above described.

The patient is to bathe his feet in the liquid, and then cover himself up with as much covering as he can bear, the object being to produce a profuse perspiration, as the liquid penetrates the whole system, breaks up the pain, and draws it down to the feet.

I do not confine myself to the exact proportions of the ingredients above mentioned, as the same may be varied according to circumstances or severity of the case.

Having thus fully described my invention, which I entitle "Butts's Concentrated-Herb Compound," what I claim as new, and desire to secure by Letters Patent, is—

The compound above described, composed and operating substantially as and for the purposes herein set forth.

In testimony that I claim the foregoing, I have hereunto set my hand, this 14th day of September, 1868.

J. H. BUTTS.
